STOLE

Eleanor Kairalla, New York, N. Y.

Application March 8, 1952, Serial No. 18,829

Term of patent 14 years

(Cl. D3—16)

To all whom it may concern:

Be it known that I, Eleanor Kairalla, a citizen of the United States, residing at New York city, in the county of New York and State of New York, have invented a new, original, and ornamental Design for a Stole, of which the following is a specification, reference being had to the accompanying drawing forming part thereof.

Fig. 1 is a front view of a stole showing my new design;

Fig. 2 is a rear view of the stole shown in Fig. 1 and

Fig. 3 is a side view thereof.

I claim:

The ornamental design for a stole, as shown.

ELEANOR KAIRALLA.
